(57) **CLAIM**

The ornamental design for a aircraft rinse pad panel, as shown and described.

DESCRIPTION

FIG. 1 is a perspective view of the aircraft rinse pad panel of the present invention;

FIG. 2 is a top elevation view of the aircraft rinse pad panel of the present invention;

FIG. 3 is a front elevation view of the aircraft rinse pad panel of the present invention;

FIG. 4 is a rear elevation view of the aircraft rinse pad panel of the present invention;

FIG. 5 is a bottom elevation view of the aircraft rinse pad panel of the present invention; and,

FIG. 6 is a right side elevation view of the aircraft rinse pad panel of the present invention, with the left elevation view a mirror image of the right elevation view.
